Richard K. Ruch, Denver, Colo., assignor to The
Gates Rubber Company, Denver, Colo., a cor-
poration of Colorado

Application September 6, 1949, Serial No. 4,859

Term of patent 14 years

(Cl. D80—10)

To all whom it may concern:

Be it known, that I, Richard K. Ruch, a citizen
of the United States, residing at city and county
of Denver and State of Colorado, have invented
a new, original, and ornamental Design for Dis-
play Stand for Garden Hose, of which the fol-
lowing is a specification, reference being had to
the accompanying drawing, forming part thereof:

In the drawing:

Figure 1 is a front plan view of a display stand
for garden hose, showing my new design; and

Figure 2 is a side elevation thereof.

I claim:

The ornamental design for a display stand for
garden hose, as shown.

RICHARD K. RUCH.
